US00D979567S

(12) **United States Design Patent** (10) Patent No.: **US D979,567 S**
(45) Date of Patent: **** Feb. 28, 2023**

(54) **HEAD-MOUNTED DISPLAY**

(71) Applicant: **Meta Platforms Technologies, LLC**,
Menlo Park, CA (US)

(72) Inventors: **Quintin Morris**, Seattle, WA (US);
Brett Delainey Christie, Seattle, WA (US);
Mauricio Romano, Redmond,
WA (US); **Peter Wesley Bristol**,
Seattle, WA (US); **Scott Andrew**
Dallmeyer, Seattle, WA (US); **Chunli**
Chen, Seattle, WA (US); **Shane**
Michael Ellis, Elmvale (CA); **Enric**
Vial Roig, Seattle, WA (US)

(73) Assignee: **Meta Platforms Technologies, LLC**,
Menlo Park, CA (US)

(**) Term: **15 Years**

(21) Appl. No.: **29/849,869**

(22) Filed: **Aug. 15, 2022**

Related U.S. Application Data

(63) Continuation of application No. 29/797,457, filed on
Jun. 30, 2021, which is a continuation of application
No. 29/754,559, filed on Oct. 12, 2020, now Pat. No.
Des. 925,530, which is a continuation of application
No. 29/723,785, filed on Feb. 10, 2020, now Pat. No.
Des. 925,529.

CLAIM

The ornamental design for a head-mounted display, as
shown and described.

DESCRIPTION

FIG. 1 is a front perspective view of a head-mounted display
showing the claimed design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines shown in the figures illustrate portions of
the head-mounted display that form no part of the claimed
design.

1 Claim, 6 Drawing Sheets
